CLAIM

The ornamental design for a vermicomposter bin with guide rails, as shown and described.

DESCRIPTION

FIG. 1 is a perspective view of the vermicomposter bin with guide rails;

FIG. 2 is a side view;

FIG. 3 is the other side view;

FIG. 4 is a front view;

FIG. 5 is a back view;

FIG. 6 is a top view; and,

FIG. 7 is a bottom view.

The broken lines represent portions of the vermicomposter bin with guide rails and form no part of the claimed design.
